UNITED STATES PATENT OFFICE.

HERBERT F. WHITTIER, OF LAWRENCE, MASSACHUSETTS.

DISK WATER-METER.

SPECIFICATION forming part of Letters Patent No. 501,287, dated July 11, 1893.

Application filed June 22, 1892. Serial No. 437,559. (No model.)

To all whom it may concern:

Be it known that I, HERBERT F. WHITTIER, of Lawrence, county of Essex, State of Massachusetts, have invented an Improvement in 5 Water-Meters, of which the following description, in connection with the accompanying drawings, is a specification, like letters and figures on the drawings representing like parts.

This invention relates to water meters of 10 the class known as disk meters, a type of which is shown in United States Patent No. 427,485.

The principle of operation of meters of this 15 class is fully disclosed in the patent referred to and inasmuch as this invention relates solely to the speed-reducing mechanism by which the movement of the disk is transmitted to the indicating mechanism, I have herein shown and shall describe only so much of 20 the mechanism of the meter as is necessary to a full and clear understanding of this invention.

The object of this invention is to improve 25 and simplify the speed-reducing mechanism of the meter and to this end the speed is reduced by the connection between the disk and the operating spindle for the indicating mechanism, said connection consisting of two positively engaging members one of which is fast 30 on the spindle, and the other of which moves with the disk.

Figure 1 of the drawings shows a water meter embodying this invention, a portion of the casing of the meter being broken away to 35 display the speed-reducing mechanism. Fig. 2 is a top or plan view of the disk; Fig. 3, a detail showing one form of connection between the disk and spindle; Figs. 4 and 5, modifications to be described; Figs. 6 and 7, horizontal 40 and cross sections respectively, of the guide ring v , and Figs. 8 and 9 are modifications to be referred to.

Referring to the drawings, the disk 23 having the circular hub h and restrained from 45 rotation by the partition 62, is fitted to oscillate in the usual disk chamber and is acted upon by the water as the latter passes through the chamber and given an oscillating movement about the center of its circular hub in 50 a manner well known and therefore needing no detailed description herein, the axis of the disk by such oscillating movement describing

the surface of a cone, the apex of which coincides with the center of oscillation of the disk and hub. The circular hub h of the disk 55 in this present embodiment of my invention is made hollow to receive about the center of oscillation the circular rack n arranged with its axis coinciding with the axis of the disk 23 and with its pitch plane passing through the 60 center of oscillation of the disk. The teeth of this rack n mesh successively with the teeth on the pinion o fast on one end of the vertical spindle o' journaled in fixed bearings and extending upwardly through the mouth h' of the hub, 65 said spindle at its upper end being geared to and operating in usual manner the several indicating pointers which co-operate to indicate the quantity of water which passes through the meter. As the oscillating movement of the 70 disk 23 causes its axis a, b , to describe the surface of a cone, the apex of which coincides with the center of the hub h which is the center of oscillation, the axis of the cone being coincident with the axis of the spindle o' , the teeth 75 on the circular rack n will during such movement successively rise to the pitch plane of the pinion o and thereby engage in succession the teeth on the said pinion. The number of teeth on the rack n is either greater or 80 less than the number of teeth on the pinion o , and as the disk 23 and its rack are restrained from rotation, it follows that the successive intermeshing of the teeth on the 85 rack and pinion,—the one being restrained from rotation,—will by reason of the difference in the number of teeth, cause a slow rotation of the other. For example, if the number of teeth on the rack n be twenty-five and the 90 number of teeth on the pinion o be one more, the said pinion will be rotated a distance equal to one tooth by each oscillation of the disk. The rack n and pinion o thus constitute the two members of a speed reducing connection 95 between the disk and the spindle, one of which members is fast on the spindle and the other of which moves with the disk, the said connection thus serving not only as an actuating connection by which the spindle is rotated by the disk but also as a speed reducing connection, dispensing with the usual reducing mechanism interposed between the disk and the spindle which actuates the indicating pointers.

In order to compel the disk 23 to make a complete oscillating movement, instead of by possibility tipping directly from one inclined position, across, into a diametrically opposite inclined position, I provide the hub of the disk at its upper opening, with a guide plate or ring *v*, Fig. 6, circular in form, having its outer edge *T* beveled to run loosely in a corresponding annular channel or groove about the interior of the opening *h* in the hub; said guide plate having an opening *R* at a definite distance from the axis of the disk through which in the present instance the spindle *o'* is extended. The ring or plate *v* constitutes an eccentric guide having a fixed center of rotation, viz:—the axis of the spindle *o'* about which the eccentric is revolved by the wobbling of the disk. The opening *v'* in the plate is countersunk from both sides as shown in Fig. 7 to allow the plate to assume its different inclined positions, the said plate compelling the axis of the disk to describe the surface of a cone about the spindle *o* as an axis, and by such motion make a complete oscillation.

This invention is not restricted to the particular embodiment herein shown as the invention may be embodied in other forms of mechanisms without departing from the scope of the invention. For example, referring to Fig. 4, instead of the rack on the hub *h*, the member which moves with the hub consists of a plate provided with two projections or teeth *t*, *t'*, provided with oppositely inclined cam faces *t''*. As the tooth *t* during the oscillating movement of the disk reaches the plane of the pinion *o*, its cam face will act upon a tooth of the pinion and move the latter a certain distance to the left, the pinion to be moved a farther distance in the same direction by the inclined face of the tooth *t'* as the latter during the oscillating movement of the disk reaches the plane of the pinion. Thus the oscillating disk communicates at each oscillation a rotation of the pinion equal to the combined throw of the two inclined faces of the teeth *t*, *t'*.

Fig. 5, represents the spindle *o'* as arranged at one side of the circular hub of the disk, its pinion being engaged at each oscillation of the disk by the pin *p* projecting therefrom, said pin moving the pinion one tooth at each oscillation. If desired the spindle in Fig. 1, may have in place of the pinion *o*, a single laterally extended arm or tooth *r*, Fig. 8, which will be engaged by the inclined faces of the teeth of the rack *r'*, as the latter rise in succession to the plane of the arm, each oscillation of the disk acting to rotate the spindle a distance equal to the throw of one tooth of the rack.

Fig. 9 represents a spur pinion *s* on the spindle *o'*, which meshes with an internal toothed rack or gear *s'* on the disk, the operation being on the same principle as that in Fig. 1. 65 If desired, the engaging members of the speed reducing mechanism may consist of two bevel gears arranged like the crown gears Fig. 1.

I claim—

1. In a water meter of the class described, 70 an oscillating disk the axis of which at each oscillation is caused to describe the surface of a cone, and a fixed non-vibrating rotatable spindle, combined with a direct speed reducing mechanism between the disk and spindle, 75 the said mechanism consisting of an oscillating member on and oscillating with the disk, and a co-operating non-oscillating member on and rotatable with the spindle, whereby the oscillations of the disk as described transmit 80 a rotary motion to the spindle, substantially as described.

2. In a water meter of the class described, 85 a rotatable spindle and an oscillating disk the axis of which at each oscillation is caused to describe the surface of a cone, combined with a circular rack on and arranged about the center of oscillation of the disk, and a pinion on the spindle in mesh with the said rack, the teeth on the rack successively rising to the 90 plane of and to engage the said pinion on the spindle, substantially as described.

3. In a water meter of the class described, 95 the combination with an oscillating disk, the axis of which at each oscillation is caused to describe the surface of a cone, a fixed rotatable spindle, and an engaging connection between the disk and spindle, of an eccentric guide loosely running in said disk and having a fixed center of rotation about the axis 100 of said spindle whereby the disk is compelled always to make a complete oscillation, substantially as described.

4. In a water meter of the class described, 105 the combination with an oscillating disk, the axis of which at each oscillation is caused to describe the surface of a cone, a fixed rotatable spindle, and an engaging connection between the disk and spindle, of a guide ring loosely carried by the hub of the disk and having an eccentrically arranged opening 110 through which the spindle is extended, the axis of the latter serving as the axis of rotation of the ring, substantially as described.

In testimony whereof I have signed my 115 name to this specification in the presence of two subscribing witnesses.

HERBERT F. WHITTIER.
